UNITED STATES PATENT OFFICE.

ALBEN E. LUNDELL, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed September 8, 1917. Serial No. 120,378.

To all whom it may concern:

Be it known that I, ALBEN E. LUNDELL, a citizen of the United States, residing at New York, in the county of Bronx and State 5 of New York, have invented certain new and useful Improvements in Telephone-Exchange Systems, of which the following is a full, clear, concise, and exact description.

This invention relates to telephone exchange systems of the type employing machine switching devices, and more particularly to systems in which the setting up of a connection is controlled solely by the calling subscriber.

15 It is the object of this invention to provide an automatic system in which power-driven switches may be used, and in which the selective switches are all of the same type of construction.

20 A feature of the invention is the use of line finder switches of the panel type in which means are provided for rendering one only of a plurality of brush sets operative during movement of a brush-carrying shaft, such means being individual to each line finder switch.

25 A further feature of the invention is the provision of a novel circuit arrangement whereby an allotted finder may be started and by which the group testing operation may be accomplished.

An additional feature of the invention is an arrangement whereby a selector switch and finder switches may be released prematurely if the calling subscriber desires to abandon the call, such premature releasing means being effective only if the abandonment of the call takes place before the selector has established connection to an idle trunk. 35 If the selector has established a connection to an idle trunk, the connection at the final switch will be completed in the usual manner and the release of the switches will be controlled in the usual manner.

40 It is thought that the invention will best be understood from the following detailed description, reference being had to the accompanying drawings.

In the drawings, Fig. 1 shows the line 45 circuit of a calling subscriber and the controlling circuits of a line finder switch. In

the dotted rectangle in Fig. 1 is shown an allotting switch, the position of which determines which one of a plurality of finders, similar to that shown in Fig. 1, shall be started. In the left-hand portion of Fig. 2 is shown a line finder switch and an allotter similar to that shown in Fig. 1. In the right-hand portion of Fig. 2 are shown control circuits for a directly operable selector switch; a final switch and the line of a called station being indicated to the right of the selector switch. In Fig. 3 are shown sender control circuits and an arrangement whereby registering switches may be set in accordance with the designation of the wanted line under the control of the calling subscriber. The wipers and contacts, shown above the dotted lines in Fig. 3, are arranged to be controlled by a single escape magnet, 50 the wipers all being mounted on the same shaft. The apparatus indicated within the dotted lines in the lower left-hand portion of Fig. 3 is under the control of the sequence switch associated therewith. Within the dotted lines in the lower right-hand portion of Fig. 3, is shown a set of step-by-step registers, a wiper, shown immediately above each stepping magnet, being individual to each such stepping magnet. 55

The line finder switches shown in Figs. 1 and 2, and the selector switch shown in Fig. 2, are similar in mechanical structure to the switch shown in Patent No. 1,123,696, issued to E. B. Craft and J. N. Reynolds. The 60 various controlling sequence switches are of the type shown in Patent No. 1,127,808, issued to J. N. Reynolds and C. F. Baldwin, and the side switch shown in Fig. 3, is of the type disclosed in Patent No. 1,252,420, 65 issued January 8, 1918, to O. F. Forsberg. The side switch in the present case is, however, arranged to have six positions and the wipers are arranged to be moved into their second position upon the first energization 70 of the escape magnet, being released into their subsequent positions upon the deenergization of the escape magnet.

75 The operation of the system is as follows.

The subscriber, whose substation is indicated at 11, when desiring to establish a 80 connection to the subscriber whose substa-

tion is indicated at 12, removes his receiver (not shown) from the switchhook, whereupon a circuit will be completed from grounded battery, winding of group relay 13, winding of individual line relay 14, inner armature and back contact of cut-off relay 15, the loop of the calling subscriber's line, outer armature and back contact of cut-off relay 15, to ground. The subscribers' lines arranged to be served by the line finders, similar to the line finder indicated in Fig. 1, are divided into groups, there being a relay corresponding to relay 13 associated with each such group.

Upon the energization of relay 13 a circuit is completed from grounded battery, lower contact of sequence switch spring 102, left and right-hand windings of relay 16 in series, lower contact of sequence switch spring 103, conductor 17, armature and front contact of relay 13, conductor 18, allotter contact 202, in position 1, normal commutator segment 19, commutator brush 20, to ground. It is to be understood that all the line finders which serve the lines in which the calling line is included are multipled to lead 17 and thence to conductor 18 in the manner described, but, due to the action of the allotter switch 200, only one of these switches can be resting in position 1 at any given time and, therefore, only the relay 16 associated with such allotted finder will be energized.

Upon the energization of relay 16 a circuit is completed from grounded battery, power magnet of sequence switch 100, upper contact of sequence switch spring 104, right-hand armature and front contact of relay 16 to ground, for moving this sequence switch out of position 1 and into position 2, under the control of its normal spring 101.

In position 2 of sequence switch 100 a circuit is completed from grounded battery, winding of up-drive magnet 21, lower contact of sequence switch spring 104, right-hand armature and front contact of relay 16, to ground. When brush shaft 22 is elevated under the control of magnet 21 it causes a plurality of brush sets, similar to the set indicated at 23, 24 and 25, to be moved into a position wherein one of them may be tripped to become operative with respect to the terminals in a contact bank of the panel type.

When the group test brush 20 engages the first commutator test segment 26 the energizing circuit of relay 16 is maintained over a circuit from grounded battery, lower contact of sequence switch spring 102, windings of relay 16, lower contact of sequence switch spring 103, conductor 17, armature and back contact of group relay 13", conductor 27, commutator segment 26, brush 20, to ground. When the brush 20 engages the third commutator segment 26, which is as-

sumed to be the segment controlled by the group relay 13 associated with the group of a calling line, the circuit of magnet 16 is opened, since the armature of relay 13 is resting on its front contact and no circuit to segment 26 can be completed. Relay 16 thereupon retracts its armature, breaking the circuit of up-drive magnet 21, thus bringing the brush shaft 22 to rest in a position wherein the third set of brushes may be tripped. The deenergization of relay 16 also completed a circuit from grounded battery, power magnet of sequence switch 100, upper contact of sequence switch spring 105, right-hand armature and back contact of relay 16, to ground, for moving this sequence switch out of position 2 and into position 3.

In positions 2 to 3 of sequence switch 100 a circuit is completed for trip magnet 28 from grounded battery, winding of magnet 28, lower contact of sequence switch spring 106, right-hand armature and back contact of relay 16, to ground. The trip magnet moves a trip rod into position so that on the subsequent upward movement of the shaft 22 the set of brushes indicated at 23, 24 and 25 will be released.

In position 3 of sequence switch 100 the circuit of up-drive magnet 21 is again completed from grounded battery, up-drive magnet 21, upper contact of sequence switch spring 106, right-hand armature and back contact of relay 16, to ground. While the test brush 25 is passing over terminal 29 of busy or non-calling lines, relay 16 remains deenergized, due to the presence of ground potential or reduced battery potential on such terminal 29. However, when the terminal 29, associated with the calling line, is engaged by the brush 25 a circuit is completed from grounded battery, right-hand winding of relay 14, which was energized in the original line circuit, right-hand armature and front contact of relay 14, winding of cut-off relay 15, terminal 29, brush 25, upper contact of sequence switch spring 103, the windings of relay 16, upper contact of sequence switch 102, to ground. Relays 15 and 16 are energized in this circuit, relay 15 operating to remove the control of the line relay in the well-known manner and allowing the group relay 13 to be deenergized so that other subscribers in the same group may initiate calls. The energization of relay 16 opens the circuit of up-drive magnet 21 and brings the brushes to rest in engagement with the terminals of the desired line. A circuit is at the same time completed from grounded battery, power magnet of sequence switch 100, upper contact of sequence switch spring 104, right-hand armature and front contact of relay 16, to ground, for moving the sequence switch 100 out of position 3 and into position 1.

As soon as sequence switch 100 leaves

position 3 relay 16 locks up through its left-hand armature and the contact of sequence switch spring 107 to ground, thereby shunting out its high resistance left-hand winding and sufficiently reducing the potential on terminal 29 so that the marginal test relay 16 of another hunting finder will not energize when its test brush engages a multiple of terminal 29.

10 As soon as sequence switch 100 arrives in position 4 a circuit is completed from grounded battery, winding of relay 32, lower contact of sequence switch spring 108, brush 24, terminal 30, loop of the calling subscriber's line, terminal 31, brush 23, lower contact of sequence switch spring 109 to ground. Relay 32 is energized in this circuit and completes a circuit from grounded battery, winding of group relay 33, armature and front contact of relay 32, upper contact of sequence switch spring 110, to ground. Relay 33 is common to a group of trunks terminating in primary line finders of the type whose operation has just been described. Upon the energization of relay 33 a secondary line finder which has been allotted by means of an allotting switch 400, is started in the same manner in which the primary line finder was started. The operation of the sesondary line finder is substantially similar to that of the line finder just described.

When relay 33 was energized a circuit was completed from grounded battery, lower contact of sequence switch spring 302, windings of relay 34, lower contact of sequence switch spring 303, conductor 35, armature and front contact of group relay 33, conductor 36, a lotter spring 402 (in position 1), normal commutator segment 37, commutator brush 38, to ground. Relay 34 upon energization completes a circuit from grounded battery, power magnet of sequence switch 300, contact 304, right-hand armature and front contact of relay 34, to ground, for moving the sequence switch 300 out of position 1 and into position 2, under the control of its normal spring 301.

In position 2 of sequence switch 300 a circuit is completed from grounded battery, winding of up-drive magnet 39, lower contact of sequence switch spring 304, right-hand armature and front contact of relay 34, to ground. The brush shaft 40 is elevated under the control of magnet 39 and a plurality of brush sets, similar to the set including brushes 41, 42 and 43, are moved into a position wherein they may be tripped by the action of trip magnet 44. The brush 38 tests for the group of trunks in which the incoming trunk is located, in a manner similar to that described in connection with the line finder shown in Fig. 1. In this case it has been assumed that the incoming trunk is one of a group served

by the first brush set of the secondary line finder. Therefore, as soon as the brush 38 engages the first group test segment 645, the circuit of relay 34 will be opened, since relay 33 is in an actuated condition, and relay 34 will be deenergized, opening the circuit of the up-drive magnet 39 to bring the brush shaft 40 to rest in a position wherein the first brush set may be tripped. At the same time a circuit is completed from grounded battery, power magnet of sequence switch 300, upper contact of sequence switch spring 305, right-hand armature and back contact of relay 34, to ground, for moving this sequence switch out of position 2 and into position 3.

The deenergization of relay 34 also completed a circuit for the trip magnet 44 from grounded battery, winding of magnet 44, lower contact of sequence switch spring 306, right-hand armature and back contact of relay 34, to ground. The energization of the trip magnet 44 operates the tripping rod (not shown) to engage a positioned set of brushes so that on subsequent upward movement of shaft 40 they will be released into engagement with the terminals of the contact bank.

In position 3 of the sequence switch 300 the brush rod 40 is again advanced under the control of magnet 39, the energizing circuit for magnet 39 extending from grounded battery, winding of magnet 39, upper contact of sequence switch spring 306, right-hand armature and back contact of relay 34, to ground. While the test brush 43 is passing over test terminals 45, associated with busy or non-calling trunks, relay 34 will not be energized, since, in the first case, there will be an absence of potential on the test terminals 45 and in the second case there will be sufficiently reduced potential to prevent the operation of the marginal test relay 34. When the brush 43 engages the test terminal of the trunk over which the call is being extended a circuit is completed from grounded battery, upper contact of sequence switch spring 111, winding of the relay 46, terminal 45, brush 43, upper contact of sequence switch spring 303, windings of relay 34, the upper contact of sequence switch spring 302, to ground. Relays 46 and 34 are energized in this circuit, relay 34 completing a circuit from grounded battery, power magnet of sequence switch 300, upper contact of sequence switch spring 304, right-hand armature and front contact of relay 34, to ground, for moving sequence switch 300 out of position 3 and into position 4.

In position 4 of sequence switch 300 relay 34 locks itself to ground through its left-hand armature and the contact of sequence switch spring 307, thus shunting out its high resistance left-hand winding and suf-

sufficiently reducing the potential on test terminal 45 to render the multiple terminals of this trunk non-selectable to other hunting finders. Relay 34 upon energization broke at its right-hand armature and back contact the energizing circuit of magnet 39. This magnet thereupon deenergized, bringing the tripped brush set to rest on the terminals of the proper trunk.

- 10 Relay 46, when energized, locks itself to
grounded battery through its right-hand armature and front contact and at its left-hand armature and front contact completed
15 a circuit from grounded battery, power magnet of sequence switch 100, lower contact of sequence switch 105, left-hand armature and front contact of relay 46 to ground, for moving this sequence switch out of position
20 13 and into position 14, which is the talking position.

When sequence switch 100 arrived in position 4, a circuit was completed from grounded battery, power magnet of allotting sequence switch 200, upper left-hand contact of sequence switch spring 112, allotter spring 203, to ground, whereupon allotter 200 was moved into a position to move another finder into position 1, from which position it may be started in response to the initiation of the next call. Similarly, when sequence switch 300 arrives in position 4 a circuit is completed from grounded battery, power magnet of allotting sequence switch 400, lower contact of sequence switch spring 308, allotter spring 403, to ground, for moving this allotter into a position wherein another secondary line finder may be moved out of position 17 and into position 18.

- 40 When the sequence switch 300 arrived in position 17 upon its restoration after a preceding use, it remained in such position until allotter 400 arrived in position 1. When the allotter arrived in position 1 a circuit 45 was completed from grounded battery, power magnet of sequence switch 300, upper contact of sequence switch spring 308, contact of allotter spring 403, to ground, for moving sequence switch 300 out of position 50 17 and into position 18. When the sequence switch 300 arrived in position 18 a circuit was completed from grounded battery, winding of an escape magnet 47, side-switch wiper 48 and its first contact, conductor 49, lower 55 contact of sequence switch spring 309, to ground. The magnet 47 was energized and moved the side switch into its second position.

With the side-switch wipers in their second position a circuit was completed from grounded battery, power magnet of sequence switch 300, lower contact of sequence switch spring 305, conductor 50, wiper 51 and its second contact, sequence switch spring 515, upper armature and back contact of relay

60, armature and back contact of relay 54 to ground, for moving sequence switch 300 out of position 18 and into position 1. The subsequent operation is accomplished as set forth in the preceding description.

It is to be understood that in practice there would be a plurality of sending equipments, such as shown in Fig. 3, less in number than the number of secondary line switches, and that they would be associated with the desired link circuits by means of a cord finder switch of any desired type. This cord finder switch has been omitted in order to simplify the description of operation of the system, and it has been assumed that a sending equipment, such as shown in Fig. 3, is permanently associated with each secondary finder circuit.

The setting of the registers under the control of the calling subscriber's impulse dial will now be described. As soon as the secondary line finder brushes 41, 42 and 43 were positioned on the terminals 52, 53 and 45 of the trunk over which the call is being extended and sequence switch 300 moved out of position 3, a circuit was completed for line relay 54, this circuit extending from grounded battery, left-hand winding of relay 54, conductor 55, lower contact of sequence switch spring 310, brush 42, terminal 53, trunk conductor 56, upper contact of sequence switch spring 108, brush 24, terminal 30, the loop of the calling subscriber's line including an impulse sending device 57, terminal 31, brush 23, upper contact of sequence switch spring 109, trunk conductor 58, terminal 52, brush 41, the lower contact of sequence switch spring 311, conductor 59, right-hand winding of relay 54, to ground. 85 90 95 100

Relay 54 attracts its armature and completes a circuit for slow release relay 60 from grounded battery, winding of relay 60, armature and front contact of relay 54, to ground. When the subscriber operates his sending device 57 to send the first series of impulses relay 54 is intermittently deenergized. Upon the first deenergization of relay 54 a circuit is completed from grounded battery, winding of slow release relay 61, upper armature and front contact of relay 60, armature and back contact of relay 54, to ground. Relays 60 and 61 retain their armatures during the sending of series of impulses. The energization of relay 61 completes a circuit from grounded battery, winding of escape magnet 47, side-switch wiper 48 in its second position, armature and front contact of relay 61, to ground. The escape magnet is energized but does not release the side-switch wipers. Each deenergization of relay 54 causes the thousands register wiper 62 to be advanced one step under the control of a stepping magnet 63, the circuit of this stepping magnet being from grounded battery, winding of magnet 63, side-switch 130

wiper 64 in its second position, upper armature and front contact of relay 60, armature and back contact of relay 54, to ground. After the first series of impulses has been sent relay 54 remains energized for a comparatively long period of time and relay 61 is allowed to deenergize, causing in turn the deenergization of escape magnet 47. Magnet 47, when deenergized, releases the side-switch wipers into their third position.

The operation of setting the hundreds register upon the receipt of the next series of impulses is identical with that previously described, except that in this case the hundreds register wiper 65 is advanced under the control of stepping magnet 66, the circuit of magnet 66 being extended through side-switch wiper 64 in its third position. Upon the termination of the second series of impulses the side switch is moved into its fourth position upon the deenergization of escape magnet 47, as previously described.

With the side-switch wipers in their fourth position the tens register wiper 67 is advanced under the control of the stepping magnet 68 through the side-switch wiper 64, in its fourth position, and upon the completion of this series of impulses, the side switch is moved into its fifth position, as described.

In the fifth position the side switch for the units register wiper 69 is positioned in response to the operation of its stepping magnet 70 through the side-switch wiper 64 in its fifth position, and upon the termination of the last series of impulses the side switch is moved into its sixth position.

When side-switch wiper 71 arrived in its third position a circuit was completed from grounded battery, power magnet of sequence switch 500, upper left contact of sequence switch spring 502, side-switch wiper 71 and its third contact, to ground, for moving this sequence switch out of its first and into its second position under the control of its normal spring 501. A circuit is then completed for line relay 72 from grounded battery, contact of sequence switch spring 312, conductor 73, winding of stepping relay 74, left-hand armature and back contact of the No. 0' counting relay, contact of sequence switch spring 503, to ground. Relays 72 and 74 are energized in this circuit, relay 72 completing a circuit from grounded battery, power magnet of sequence switch 300, upper left-hand contact of sequence switch spring 313, front contact and armature of relay 72, to ground, for moving this sequence switch out of position 4 into position 5. In position 5 a circuit is completed from grounded battery, winding of power magnet 75, right-hand upper contact of sequence switch spring 313, armature and front contact of relay 72, to ground. A selector brush shaft 76 is moved upwardly under

the control of magnet 75 to advance a plurality of brush sets corresponding to the one including brushes 77, 78 and 79 into a position wherein one of such sets may be tripped.

The registers indicated by the wipers 62, 65, 66 and 69 and their associated contacts are set in accordance with the numerical designation of the wanted line. Other contacts and wipers (not shown) are associated with the registers and are electrically connected in such a manner as to control the translation of the number of the wanted line so that the proper impulses will be sent out to control 500-point switches to establish connection to the wanted line. Since the translation into the desired sets of impulses is well-known in the art, it has not been considered necessary to disclose the wiring arrangement of the registers in the present description. If, however, we assume that the number of the wanted line is 7823, it will be necessary to trip the fourth set of brushes and establish connection to an idle trunk in the fourth sub-group of the switch shown in Fig. 2. At the final switch, which is indicated in Fig. 2, it will be necessary to trip the third set of brushes and then establish connection to the fourth line in the third sub-group served by such brush. Therefore it will be necessary to send out four incoming brush selecting impulses, four incoming group selecting impulses, three final brush selecting impulses, three tens selecting impulses and four units selecting impulses.

The energizing of relay 74 completed a circuit from grounded battery, winding of the No. 3 counting relay (not shown) armature and back contact of the No. 3' counting relay (not shown) a contact of the register controlled by wiper 62, conductor 80, upper left-hand contact of sequence switch spring 504, armature and front contact of stepping relay 74, to ground. It will be remembered that the energization of relay 72 caused the brush shaft 76 to be moved upwardly. As soon as commutator brush 81 engages the first conducting segment of commutator 82, the stepping relay 74 is shunted over a path from grounded battery, winding of relay 72, conductor 83, lower contact of sequence switch spring 314, commutator 82, brush 81, to ground. The resultant deenergization of stepping relay 74 allows the No. 3' counting relay to energize in the well-known manner. The counting relays are actuated successively as the brush 81 successively passes over conducting segments of the commutator 82, and when the 0' counting relay is energized, the lower branch of this circuit of relay 72 is permanently opened at the left-hand armature of the 0' counting relay, and when a moment later brush 81 engages an insulating

segment of commutator 82, this relay de-energizes, breaking the circuit of the up-drive magnet 75 and bringing the brush shaft 76 to rest in a position wherein the 5 fourth set of brushes may be tripped.

The counting relays, when energized, lock up to ground through sequence switch spring 505. The 0' counting relay at its right-hand armature completed a circuit 10 from grounded battery, power magnet of sequence switch 500, lower contact of sequence switch spring 506, right-hand armature and front contact of the 0' counting relay to ground, for moving this sequence switch out of position 2 and into position 3. During this movement the locking circuit 15 of the counting relays is broken at sequence switch spring 505 and they are restored.

The deenergization of relay 72 completed 20 a circuit from grounded battery, winding of the power magnet of sequence switch 300, upper contact of sequence switch spring 315, armature and back contact of relay 72, to ground, for moving this sequence switch 25 out of position 5 and into position 6.

In position 6 of sequence switch 300 a circuit is completed from grounded battery, winding of trip magnet 612, contact of sequence switch spring 318 to ground, the 30 operation of this trip magnet resulting in the movement of a trip rod (not shown) to engage a positioned set of brushes so that, on subsequent upward movement of the shaft, these brushes will be released and rendered operative with relation to the 35 group of terminals served by them.

Provided the register setting operation has advanced to a stage wherein the side switch has reached its fourth position or 40 some later position, thereby insuring that the hundreds register has been set, a circuit is completed from grounded battery, winding of the power magnet of sequence switch 500, the upper right or one of the lower 45 contacts of sequence switch spring 502, and side-switch wiper 71 in either its fourth, fifth or sixth position, to ground, for moving this sequence switch out of position 3 and into position 4.

A circuit is now completed from grounded 50 battery, winding of relay 72, contact of sequence switch spring 312, conductor 73, winding of relay 74, left-hand armature and back contact of the 0' counting relay, contact of sequence switch spring 503, to ground. Relays 72 and 74 are energized in 55 this circuit as before. Relay 72 completed a circuit from grounded battery, power magnet of sequence switch 300, left-hand contact of sequence switch spring 313, armature and front contact of relay 72, to ground, for moving this sequence switch out of position 6 and into position 7. The energization of relay 72 also completed a circuit 60 from grounded battery, winding of the up- 65

drive magnet 75, right-hand contact of sequence switch spring 313, armature and front contact of relay 72 to ground. The selected brush set is now advanced in a group selecting movement. The energization of 70 the stepping relay 74 completed a circuit from grounded battery, winding of the No. 3 counting relay (not shown) armature and back contact of the No. 3' counting relay (not shown) through contacts controlled 75 jointly by the thousands and hundreds registers, wiper 65, upper right-hand contact of sequence switch spring 504, armature and front contact of relay 74 to ground. When the commutator brush 84 engages a conducting segment of commutator 85, the stepping relay is shunted by a circuit extending from grounded battery, winding of relay 72, conductor 83, upper contact of sequence switch spring 314, commutator 85, brush 84, to ground. The deenergization of the stepping relay 74 allows the No. 3' counting relay to energize. The counting relays are actuated in the well-known manner, and when the No. 0' counting relay is energized, 80 which occurs when the selected brush is just below the first terminal in the fourth subgroup, the lower branch of the energizing circuit of relay 72 will be broken. When, a 85 moment later, brush 84 engages an insulated segment of commutator 85, at which time the brushes will be accurately centered in their desired position, the relay 72 is deenergized, breaking the circuit of up-drive magnet 75 and bringing the brushes 90 to rest in the desired position. The deenergization of relay 72 completed a circuit from grounded battery, power magnet of sequence switch 300, upper contact of sequence 95 switch spring 315, and the armature and back contact of relay 72 to ground, for moving this sequence switch out of position 7 and into position 8. The energization of the 0' counting relay completed a circuit from grounded battery, winding of power 100 magnet of sequence switch 500, lower contact of sequence switch spring 506, right-hand armature and front contact of the 0' counting relay to ground, for moving this sequence switch out of position 4 and into 105 position 5. On leaving position 4 the locking circuit of the counting relays is broken at sequence switch spring 505 and they are restored. If the register setting operation 110 has been advanced to a stage such that side-switch wiper 71 is in either its fifth or sixth position, a circuit will then be completed from grounded battery, power magnet of sequence switch 500, one of the lower contacts of sequence switch spring 502, and side-switch wiper 71 in its fifth or sixth 115 position, to ground, for moving this sequence switch out of position 5 and into position 6.

In position 8 of sequence switch 300, a 120

circuit is completed from grounded battery, winding of up-drive magnet 75, left-hand contact of sequence switch spring 316, armature and back contact of test relay 184, to ground. The selected brush set is now advanced to hunt for an idle trunk in the selected group. If we assume that idle trunks are characterized by full battery potential on their test terminals 611, and that busy trunks are characterized by reduced potential on their test terminals, the relay 184 will not be energized while test brush 79 is passing over the terminals of busy lines. As soon as brush 79 engages a terminal having full battery potential thereon, a circuit will be completed from grounded battery, terminal 611, brush 79, the windings of relay 184 in series, right-hand contact of sequence switch spring 317, armature and back contact of relay 72, to ground. Relay 184 is energized in this circuit and opens the circuit of up-drive magnet 75, thereby bringing the brush set to rest on the terminals of an idle trunk.

25 A circuit is also completed by the energization of relay 184 from grounded battery, power magnet of sequence switch 300, conductor 86, lower contact of sequence switch spring 319, right-hand armature and front contact of relay 184, to ground, for moving this sequence switch out of position 8 and into position 10.

30 Test relay 184 short-circuited its high resistance left-hand winding through its left-hand armature and front contact and resistance 93, and the left-hand contact of sequence switch spring 317, as soon as it was energized, and after sequence switch 300 arrives in position 9, this short circuit is maintained at the upper contact of sequence switch spring 309. This short-circuiting of the high resistance left-hand winding of relay 184 sufficiently reduces the potential on the multiples of test terminal 611 to render the trunk line non-selectable to other testing selectors.

35 In position 10 of sequence switch 300, the control circuit is extended to a succeeding final switch over conductor 73, through the lower contact of sequence switch 320, brush 77, terminal 87, to a relay at the final switch, corresponding to relay 72, to control selections at such switch. The sender sequence switch 500 is moved through positions 6, 8 and 10 to control the selections at the final switch. When sequence switch 500 is moved out of position 10 upon the last energization of the 0' counting relay, it is moved into position 14.

40 While sequence switch 500 was passing through positions 11 to 14, a circuit is completed from grounded battery, winding of side-switch release magnet 94, conductor 95, contact of sequence switch spring 508 to ground. Magnet 94, upon energization,

locks itself to ground through its armature and front contact and off-normal contact 96, and causes the restoration of the side switch.

45 In position 14 of sequence switch 500 a circuit is completed from grounded battery, 70 winding of stepping magnet 63 of the thousands register, its armature and back contact, off-normal contact 88, upper left-hand contact of sequence switch spring 507, to ground. The stepping relay 63 is energized 75 and interrupts its own circuit to advance the thousands register through a complete cycle of rotation and into its normal position at which time the off-normal spring 88 will open its upper contact and close its lower 80 contact. Upon the closure of spring 88 upon its lower contact, a circuit is completed from grounded battery, power magnet of sequence switch 500, conductor 89, lower contact of spring 88, upper left-hand contact of sequence switch spring 507, to ground, for moving this sequence switch out of position 14 and into position 15.

50 In position 15 stepping magnet 66 is operated through the upper contact of off-normal spring 90 and the upper right-hand contact of sequence switch spring 507, to restore the hundreds register to its normal position. On reaching its normal position the opening of the upper contact of spring 90 prevents further operation of magnet 66, and by closing the lower contact of spring 90 completes a circuit for moving the sequence switch 500 out of position 15 and into position 16. In position 16 the magnet 68 is 100 intermittently energized to restore the tens register through the upper contact of off-normal spring 91 and the lower right-hand contact of sequence switch spring 507, and upon its arrival in normal position, moves sequence switch 500 into position 17, as previously described. In position 17 stepping magnet 70 is intermittently energized through the upper contact of off-normal spring 92 to restore the units register to 105 its normal position, and upon its arrival in normal position, moves the sequence switch 500 out of position 17 and into position 18.

55 A circuit is then completed from grounded battery, power magnet of sequence switch 500, upper contact of sequence switch spring 506, side-switch wiper 71 and its first contact, to ground, for moving this sequence switch out of position 18 and into position 1. 115

60 It is to be observed that side-switch wiper 51, in reaching its first contact completes a circuit from grounded battery, power magnet of sequence switch 300, lower contact of sequence switch spring 305, conductor 50, side-switch wiper 51 and its first contact, conductor 604, sequence switch spring 322, to ground, for moving this sequence switch out of position 10 and into position 14, 125 which is the talking position. The connection 130

is now completed and the subscribers may converse.

When sequence switch 300 arrived in position 11, supervisory relay 97 was energized over the calling line circuit and caused in turn the energization of relay 72 over a circuit from grounded battery, winding of relay 72, armature and front contact of relay 97, to ground.

- 10 When connection is no longer desired, the calling subscriber replaces his receiver, causing the deenergization of relay 97, which in turn causes the deenergization of relay 72. A circuit is then completed from 15 grounded battery, power magnet of sequence switch 300, upper contact of sequence switch spring 315, armature and back contact of relay 72, to ground, for moving sequence switch 300 out of position 14 and into position 15. A circuit is now completed from 20 grounded battery, winding of down-drive magnet 98, lower contact of sequence switch spring 315, armature and back contact of relay 72, to ground. At the same time a 25 circuit is completed from grounded battery, winding of down-drive magnet 99, right-hand contact of sequence switch spring 316, right-hand armature and back contact of relay 184, to ground. Relay 184 was deenergized when sequence switch 300 left position 30 14, its locking circuit having been broken at sequence switch spring 309. The brush shafts 40 and 76 are restored under the control of magnets 98 and 99 respectively. Assuming that the brush shaft 40 is the first to reach its normal position, a circuit will be completed from grounded battery, winding of relay 72, conductor 83, contact of sequence switch spring 321, commutator segment 600, brush 601, to ground. Relay 72 35 is energized and opens the circuit of down-drive magnet 98. When brush shaft 76 arrives in its normal position, a circuit is completed from grounded battery, power magnet of sequence switch 300, conductor 86, upper contact of sequence switch spring 319, normal commutator segment 602, brush 84, to ground, for moving sequence switch 300 out of position 15 and into position 16. 40 Since relay 72 is energized, a circuit will be at once completed from grounded battery, power magnet of sequence switch 300, left-hand contact of sequence switch spring 313, armature and front contact of relay 72, to 45 ground, for moving this sequence switch out of position 16 and into position 17.
- If the brush rod 76 is the first to reach its normal position, sequence switch 300 will be moved out of position 15 and into position 16, as described, and the restoration of brush shaft 40 will continue in position 16 of this sequence switch. When brush shaft 40 reaches its normal position, relay 72 will be energized and will cause sequence switch 300 to be moved out of position 16

and into position 17. Sequence switch 300 remains in position 17 until moved into position 18 by the action of allotter switch 400, and is then moved out of position 18 and into position 1 by the action of the 70 sender controlling side switch, as previously described.

The final connecting switch is restored in the well-known manner when the brush set 75 77, 78 and 79 leaves the terminals of the trunk leading to such final switch.

When test brush 43 moves downward from terminals 45, the locking circuit of relay 46 is broken and this relay deenergizes, completing a circuit from grounded battery, power magnet of sequence switch 100, lower contact of sequence switch spring 113, left-hand armature and back contact of relay 46 to ground, for moving this sequence switch out of position 14 and into position 15.

In position 15 of sequence switch 100, a circuit is completed from grounded battery, the winding of down-drive magnet 603, the lower contact of sequence switch spring 110, to ground. The brush shaft 22 is restored to its normal position under the control of magnet 603, and when it reaches its normal position, a circuit is completed from grounded battery power magnet of sequence switch 100, upper contact of sequence switch spring 113, normal commutator segment 604, commutator brush 605, to ground, for moving this sequence switch out of position 15 and into position 18. On leaving position 15 the circuit of magnet 603 is opened.

Sequence switch 100 remains in position 18 awaiting the action of allotter 200, and when this allotter arrives in position 1, sequence switch 100 will be moved into position 1, thereby rendering the finder switch ready for reoperation. When brush 25 moved off of terminal 29, line relay 14 and cut-off relay 15 were deenergized. All the apparatus has now been restored to normal 110 and is ready for reuse.

If the called line is busy, a busy tone will be applied to the talking circuit by means of a busy-back apparatus at the final switch in a manner well-known in the art, and the calling subscriber upon hearing this tone will replace his receiver and cause the release of the switches, as previously described.

If the calling subscriber desires to abandon the connection after his line has been seized by the line finder but before any impulses have been sent, the system will operate as follows. It will be remembered that the sender controlling side switch was moved into position 2 as soon as the secondary line finder was allotted for use by the action of allotter switch 400. Therefore, when sequence switch 300 moves into position 4 upon the seizure of the incoming trunk line by 120 125 130

its associated line finder, it will immediately be moved out of position 4 by a circuit from grounded battery, power magnet of sequence switch 300, lower contact of sequence switch spring 305, conductor 50, side-switch wiper 51 in its second position, sequence switch spring 515, upper back contact and armature of relay 60, back contact and armature of relay 54, to ground, and will come to rest in position 5. Since the sender sequence switch 500 has not been moved out of position 1, the fundamental circuit will not be completed and relay 72 remains deenergized. A circuit is then completed from grounded battery, power magnet of sequence switch 300, upper contact of sequence switch spring 315, armature and back contact of relay 72, to ground, for moving this sequence switch out of position 5 and into position 6. Sequence switch 300 is then immediately moved out of position 6 and into position 7 over a circuit identical with that by means of which it was moved out of position 4. On arriving in position 7 it is immediately moved into position 8 by means of the same circuit which moved it from position 5 to position 6, and is then advanced out of position 8 into position 9 by means of the circuit which moved it out of positions 4 and 6.

When the sequence switch 300 arrives in position 9, since the brush rod 76 has not been moved from its normal position, a circuit is completed from grounded battery, power magnet of sequence switch 300, conductor 86, upper contact of sequence switch spring 319, normal segment 602, brush 84, to ground, for moving this sequence switch out of position 9, through position 10 and into position 14. The sequence switch is then moved out of position 14 over a circuit from grounded battery, power magnet of sequence switch 300, upper contact of sequence switch spring 315, armature and back contact of relay 72, to ground. In position 15 of sequence switch 300, the secondary line finder switch is restored as previously described, causing in turn the restoration of the primary line finder shown in Fig. 1.

If the subscriber desires to abandon connection after having sent in one or more sets of impulses, and provided that the selector switch has not established connection to an idle trunk, the release of the selector switch will be as follows.

When the calling subscriber replaces his receiver the relay 54 deenergizes, causing in turn the deenergization of relay 60. Since at least one set of impulses has been sent the side switch is in its third position or some later position, and, therefore, upon the release of the slow-release relay 60, a circuit is completed from grounded battery, winding of side-switch release magnet 94, side-switch wiper 610 in either its third,

fourth, fifth or sixth position, and the lower armature and contact of relay 60 to ground. Relay 94 locks up to ground and causes the restoration of the side switch.

If we assume that the selector switch is being moved upwardly in its brush-selecting movement in position 5 of sequence switch 300 at the time the calling subscriber abandons the connection, the brush-selecting movement will be completed and the sequence switch 300 moved into position 6, as previously described. It will immediately be moved out of position 6 into position 7 over a circuit from grounded battery, power magnet of sequence switch 300, the lower contact of sequence switch spring 305, conductor 50, side-switch wiper 51 in its first position, conductor 604, contact of sequence switch spring 322 to ground. Sequence switch 300 will be immediately moved out of position 7 into position 8 over a circuit extending from grounded battery, power magnet of sequence switch 300, upper contact of sequence switch spring 315, armature and back contact of relay 72 to ground, and will be moved out of position 8 and into position 9 over a circuit similar to that just described for moving it out of position 6.

In position 9 of sequence switch 300, a circuit is completed from grounded battery, down-drive magnet 99, right-hand contact of sequence switch spring 316, right-hand armature and back contact of relay 184 to ground. Brush rod 76 is then restored to its normal position under the control of magnet 99. Upon arriving in normal position, a circuit is completed by way of normal commutator segment 602 from grounded battery, power magnet of sequence switch 300, conductor 86, upper contact of sequence switch spring 319, normal segment 602, brush 84, to ground, for moving this sequence switch out of position 9, through position 10 and into position 14. From this point the restoration of the selector and finder switches is accomplished as previously described.

If a subscriber replaces his receiver during the group-selecting movement of the selector switch, the restoration of the switches will be substantially as described, but in this case the group-selecting movement will be completed in position 7 of sequence switch 300 and the sequence switch will then be moved into position 8 in the usual manner. The sequence switch 300 will be moved out of position 8 and into position 9 over a circuit controlled at sequence switch spring 322 as described.

If the calling subscriber hangs up while the selector is making its trunk-hunting movement, the sequence switch 300 will be moved out of position 8 and into position 9 as described, but if a trunk has already been

seized, the movement of sequence switch 300 into position 9 will not effect the restoration of the switch, since the circuit of down-drive magnet 99 is open at the right-hand 5 arature and contact of test relay 184. In this case the sequence switch 300 will be moved into position 10 and impulses will be sent to a final connector switch in the usual manner.

10 If the calling subscriber replaces his receiver after two sets of impulses have been sent and the thousands and hundreds registers have been positioned, and if an idle trunk has been seized, the restoration of the 15 side switch will not prevent the sending of impulses to the final switch. If the sender sequence switch 500 is in some position between 4 and 6 at this time, the side switch will release, in which case ground would be 20 supplied in positions 5, 7 and 9 of sequence switch 500 through side-switch wiper 71 in its first position and the upper contact of sequence switch spring 506, for moving the 25 sequence switch to its various sending positions. In the normal positions of the tens and units registers, one impulse will be sent and will allow the sending operation to continue as previously described.

30 If the calling subscriber replaces his receiver after a trunk has been seized and after the sender sequence switch has arrived in position 6, the replacing of his receiver will not allow the side switch to release, since relay 60 is maintained energized over 35 a circuit from grounded battery, winding of relay 60, upper contact of sequence switch spring 509, to ground. When the sending of the impulses has been completed and sequence switch 500 leaves position 10 40 relay 60 deenergizes, causing the release of the side switch as previously described and allows ground to be supplied through the lower contact of sequence switch spring 322 through side-switch wiper 51 and its first 45 contact to the power magnet of sequence switch 300, for moving this sequence switch out of position 10, as previously described.

What is claimed is:

50 1. In an automatic telephone exchange system, a contact bank, multiple terminals of calling subscribers' lines arranged there-in in groups, a line finder switch including a movable shaft carrying a plurality of sets of brushes resiliently secured thereto, there being a set of brushes for each group of terminals, means for normally retaining said brush sets in inoperative position with respect to the groups of terminals to which they have access, means to advance said brush shaft in a preliminary movement of variable extent, means operated in accordance with the extent of such preliminary motion to selectively trip a desired one of said brush sets into operative relation with respect to the group of terminals served by

it, and means to advance a tripped brush set into engagement with the terminals of a calling line.

2. In an automatic telephone exchange system, a contact bank, multiple terminals of calling subscribers' lines arranged there-in in groups, apparatus individual to each of said groups, a line finder switch including a movable shaft carrying a plurality of sets of brushes resiliently secured thereto, there being a set of brushes for each group of terminals, means for normally retaining said brush sets in inoperative position with respect to the groups of terminals to which they have access, means to advance said brush shaft in a preliminary movement of variable extent, means to determine the extent of such positioning movement in accordance with the condition of the apparatus individual to the various groups, means dependent upon the extent of such preliminary motion to trip a desired one of said brush sets into operative relation with the group of terminals served by it, and means to advance said tripped brush set into engagement with the terminals of a calling line.

3. In an automatic telephone exchange system, a contact bank, multiple terminals of calling subscribers' lines arranged there-in in groups, a relay individual to each of said groups, and common to all the lines of its group in a plurality of line finder switches, each of said line finder switches including a movable shaft carrying a plurality of sets of brushes resiliently secured thereto, there being a set of brushes for each group of terminals, said brush sets being normally inoperative with respect to the group of terminals to which they have access, means to advance said brush shaft in a preliminary movement, an auxiliary brush operable in response to preliminary positioning movement of said brush shaft, test contacts arranged to be engaged by said auxiliary brush and multiplied to corresponding contacts on the various finder switches, means controlled at contacts of said group relays to vary the electrical condition of said test contacts, means to determine the extent of such preliminary positioning movement in accordance with the electrical condition of said test contacts, means dependent upon the extent of motion of said brush shaft to trip a desired one of said brush sets into operative relation to the group of terminals served by it, and means to advance an operated brush set into engagement with the terminals of a calling line.

4. In an automatic telephone exchange system, a contact bank, multiple terminals of calling subscribers' lines arranged there-in in groups, a relay individual to each of said groups and common to all the lines of its group, a plurality of line finder

switches, an auxiliary brush associated with each of said switches and operable in response to movement of its associated switch, test contacts arranged to be engaged by said auxiliary brush and multiplied to corresponding contacts on the various finder switches, means to advance one of said finder switches in a group selecting movement, a controlling circuit successively extended to said test contacts and contacts controlled by said group relays, a portion of said controlling circuit being multiplied to the armatures of said group relays, and means to determine the extent of said group selecting movement in accordance with the electrical condition of said controlling circuit.

5. In an automatic telephone exchange system, a contact bank, multiple terminals of calling subscribers' lines arranged therein in groups, a plurality of line finder switches, an auxiliary brush associated with each of said switches and operable in response to movement of its associated switch, a contact engaged by said auxiliary brush in its normal position, an allotting switch common to said line finders, contacts controlled thereby, and a starting circuit for each of said line finder switches controlled through contacts controlled by said allotter, and said auxiliary brush and its associated contact.

6. In an automatic telephone exchange system, a contact bank, multiple terminals of calling subscribers' lines arranged therein in groups, a relay individual to each of said groups, and common to all the lines of its group, a plurality of line finder switches, an auxiliary brush associated with each of said switches and operable in response to movement of its associated switch, a contact engaged by said auxiliary brush in its normal position, an allotting switch common to said line finders, contacts controlled thereby, circuits controlled at contacts of said allotting switch to move an idle finder switch into a position to be started, a starting circuit completed upon initiation of a call to start an allotted finder, said starting circuit being multiplied to the armatures of said group relays and extending from a contact of a relay individual to the group in which the call originated through a contact of said allotter switch and said auxiliary brush and its associated contact.

7. In an automatic telephone exchange system, calling and called subscribers' lines, selector switches and final switches for interconnecting said lines, means to advance a selector switch in a group selecting movement, means to advance said selector switch in a trunk selecting movement, and means under the control of a calling subscriber to cause the premature release of the selector switch, such means being operative only at a time previous to the completion of the trunk selecting movement of the selector

switch, and means operative upon such completion to prevent the release of said selector switch, until after the selected final switch has been fully positioned.

8. In an automatic telephone exchange system, calling subscribers' lines, line finder switches, selector switches, means to extend a calling subscriber's line to a selector switch by means of said line finder switches, means to advance said selector switch in a group selecting movement, means to advance said selector switch in a trunk selecting movement, and means under the control of the calling subscriber to effect the premature release of said switches, such means being operative only at a time previous to the completion of the trunk selecting movement of the selector switch, and means operative upon such completion to prevent the release of said selector switch, until after the selected final switch has been fully positioned.

9. In an automatic telephone exchange system, calling subscribers' lines and substation apparatus, line finder switches, selector switches, final switches, means to extend a calling subscriber's line to a selector switch by means of said line finder switches, means to advance a selector switch in a group selecting movement, means controllable by the calling subscriber's switchhook to effect premature release of said switches, said means being operative only at a time previous to the completion of the trunk selecting movement of the selector switch, and means to operate a final switch if said trunk selecting movement has been completed, irrespective of the condition of the calling subscriber's substation apparatus.

10. In a telephone exchange system, an incoming line, an outgoing line, an automatic switch for interconnecting said lines, a sending device, means to control said sending device, means to selectively control said switch during a portion of the operation of said sending device, circuit controlling means, release circuits controlled thereby at certain times to cause the immediate restoration of said switch and said sending device, and means effective under the control of said circuit controlling means at other times to delay the release of said switch and said sending device until after the complete operation of said sending device.

11. In a telephone exchange system, an incoming line, an outgoing line, an automatic switch for interconnecting said lines, a sending device, means to operate said sending device, means to selectively control said switch during a portion of the operation of said sending device, a relay, release circuits effective upon the operation of said relay at certain times to cause the immediate restoration of said switch and said sending device, and means effective upon the operation of said relay at other times to delay the re-

lease of said switch and said sending device until after the complete operation of said sending device.

12. In a telephone exchange system, telephone lines, means to establish an interconnection between said lines by building up a connection through a plurality of stages, means to accomplish premature release of a partially established connection prior to the accomplishment of a predetermined number of selecting stages, and means operative after the accomplishment of such predetermined number of selecting stages to prevent premature release of a connection until after a greater predetermined number of stages have been accomplished.

13. In a telephone exchange system, telephone lines, means to establish an interconnection between said lines by building up a connection through a plurality of stages, means to accomplish premature release of a partially established connection prior to the completion of the first selecting stage, and means operative after the completion of such selecting stage to prevent premature

release of a connection until after a predetermined number of stages have been accomplished.

14. In a telephone exchange system, telephone lines, automatic switches, a sending device, means to establish an interconnection between said lines by means of said automatic switches under the control of said sending device by building up a connection through a plurality of stages, means to accomplish premature release of a partially established connection prior to the accomplishment of a predetermined number of selecting stages, and means operative after the accomplishment of such predetermined number of selecting stages and partially controlled by said sending device to prevent premature release of a connection until after a greater predetermined number of stages have been accomplished.

In witness whereof, I hereunto subscribe my name this 28th day of August A. D., 1917.

ALBEN E. LUNDELL.
